UNITED STATES PATENT OFFICE.

OSCAR C. JANSSEN, OF ST. LOUIS, MISSOURI.

INTERNAL-COMBUSTION ENGINE.

Application filed June 28, 1917, Serial No. 177,463. Renewed February 7, 1924.

To all whom it may concern:

Be it known that I, OSCAR C. JANSSEN, a citizen of the United States, and a resident of St. Louis, State of Missouri, have 5 invented an Improvement in Internal-Combustion Engines, of which the following description, in connection with the accompanying drawings, is a specification, like characters on the drawings representing like parts.

10 This invention relates to internal combustion engines and more particularly to the means for controlling the admission of fuel to the cylinder, and the exhaust of the waste gases therefrom.

15 One of the objects of the invention is to provide such means for controlling the admission of fuel to the cylinder and the exhaust of the waste gases therefrom which shall be simple in construction, efficient in 20 operation and may be produced at a relatively low cost.

The invention will best be understood by reference to the following description when taken in connection with the accom-

25 panying drawing of one specific embodiment of the invention, while the scope of the invention will be more particularly pointed out in the appended claims.

30 In the drawings:

Fig. 1 is a central sectional elevation taken through the upper portion of a cylinder of an engine embodying one illustrative form of the invention;

35 Figs. 2, 3 and 4 are central sectional elevations similar to that in Fig. 1, showing the parts in different positions.

The cylinder illustrated has an outer wall 2 and an inner wall 4, forming between them the water jacket 6. A piston not 40 shown works within the cylinder chamber 8.

In the illustrative embodiment of the invention shown, the means for controlling the admission of fuel to the cylinder and the exhaust of the waste gases therefrom is 45 for convenience disposed centrally of the cylinder head, but it will be apparent that it may be otherwise suitably located, without departing from the spirit of the invention. To this end the cylinder head 10 is provided with a central cylindrical bore 12. The cylinder is provided with an admission chamber 14 extending around said bore 12 and adapted to communicate therewith by a plurality of admission ports 16. Said cylinder is also provided with an exhaust chamber 18, herein also extending

about said bore 12 and adapted to communicate with said central bore 12 through a plurality of exhaust ports 20.

A plug 22 has screw threaded connection 60 at 24 with said central bore 12, thus closing said bore, and is provided with extended portions 26 and 28 and an axial bore 30 in which is mounted for sliding movement a sleeve 32 embracing the stem 34 of a puppet valve disk 36 and movable therewith. The plug 32 with its extended portions 26 and 28 thus forms an extended and effective bearing for the sleeve 32 and stem 34 of the puppet valve 36. 70

Within the bore 12 there is fitted for sliding movement a cylindrical slide valve 38 having a central chamber 40 provided with a circular opening 42, Fig. 2, and adapted to communicate, by a plurality of lateral ports 44, with the admission ports 16 and the exhaust ports 20. Said circular opening 42 is provided around its edge with a valve seat 46 for the bevelled edge 48 of the valve disk 36. 80

From the construction described, it will be seen that the slide valve 38 controls the admission ports 16 and exhaust ports 20, while the puppet valve disk 36 controls the communication of the opening 42 of the 85 slide valve 38 with the interior of the cylinder, in the manner hereinafter more fully set forth.

A helical spring 50 surrounds the extension 26 of the plug 22, said spring having 90 bearing at one end within an annular recess 52 provided in the upper surface of the plug 22, and at its other end within a cup-shaped disk 54 provided at the upper end of the sleeve 32 and herein shown 95 as integral with the latter.

Referring to the figures, it will be noted that in the embodiment of the invention shown, the bore 12, within which the slide valve 38 operates, is not of uniform diameter throughout, that portion from the lower edge of the exhaust ports 20 downwardly being of less diameter than the upper portion of said bore, the lower portion of the slide valve 38 being accordingly of a 100 diameter to fit the lower portion of said bore 12, and the upper portion of said slide valve being of a diameter to fit the upper portion of said bore. 105

It will be noted by reference to the figures 110 that the portion of the slide valve 38 of lesser diameter extends to a point slightly

above the upper edge of the ports 44 provided in said slide, so that the annular shoulder 56 thus formed upon the outer wall of the slide valve is thus adapted to co-
5 operate with the annular shoulder 58 extended around the inner wall of the bore 12 to limit the movement of the slide valve 38 in one direction, that is to say when said valve, as will hereinafter be more fully
10 described, is in a position in which it closes the exhaust ports 20, that portion 60 of the wall of the slide valve 38, in this position of the slide valve, extending beyond the lower edge of the exhaust ports 20,
15 thus covering said ports completely and effecting a complete closure thereof.

Packing rings 62 may be provided in the outer wall of the slide valve 38, if desired, to render said slide gas-tight.

20 Any suitable actuating means may be provided for the valve, which will actuate said valve in timed relation to the movements of the piston, with reference to the admission, compression, firing and exhaust, said 25 means herein comprising a shaft 64 having a cam 66 thereon adapted to co-operate with the upper end of the valve stem 34.

It will be understood that this cam shaft may be driven through any suitable and 30 usual connections from the crank shaft of the engine.

The manner in which the valve is actuated by its actuating means will be best understood from the following description 35 of the mode of operation of my invention.

In Fig. 1, the parts are shown in the position that they occupy immediately after the explosion has taken place. It will be noted that in this figure the admission ports 16 are closed by the slide valve 38, while the 40 exhaust ports 20 are left open by the latter, said exhaust ports being in communication with the valve chamber 40 of said slide valve through the ports 44 of said slide 45 valve, but that all communication of said valve chamber 40 with the interior of the cylinder is cut off by the puppet valve 36 which is closed.

As the shaft 64 and its cam 66 rotate in a 50 contra-clockwise direction in the drawing, the projecting part 68 of said cam acts upon the upper end of the valve stem 34 and moves said valve and the sleeve 32 downwardly against the action of the spring 50 into the position shown in Fig. 2. The position of the slide valve 38 remains the same as in Fig. 1, but the valve 36 being open the exhaust chamber 18 is now in communication with the interior of the cylinder, the 55 admission ports being closed, and the exhaust gases will thus be exhausted from the cylinder upon the exhaust stroke of the piston, which now takes place.

The shaft 64 and its cam 66 continuing 60 to rotate in a contra-clockwise direction, the

high portion 70 of said cam now acts upon the upper end of the valve spindle 34 and moves said valve and sleeve 32 still further downwardly against the action of the spring 50. In this movement the lower end of the 70 sleeve 32, acting upon the upper surface 72 of the raised inner portion of the slide valve 38, carries the latter downwardly into the position shown in Fig. 3, in which position it will be noted that the exhaust 75 ports are now closed by said slide valve, while the admission ports are opened, they being in register with the ports 44 of said slide valve, and the admission chamber 14 being thus in communication with the interior of the cylinder, as the puppet valve 36 is still open.

The suction stroke of the piston now takes place, thus drawing in fresh explosive mixture from the supply.

85 The rotation of the shaft 64 and its cam 66 continuing, the raised portion 70 of said cam moves off of the upper end of the valve stem 34, thus enabling the spring 50 to raise the sleeve 32 with the valve stem 34 and valve 36 into the position shown in Fig. 4, to close said valve. The compression stroke of the piston now takes place, followed by the explosion. The compression acts upon the lower surface of the valve 36 and raises 90 said puppet valve and the slide valve 38 into the position shown in Fig. 1, before the explosion, which then follows, whereupon the same cycle of operations is ready to be 95 repeated.

100 It will be noted that in the embodiment of the invention illustrated, the spring 50 seats the puppet valve 36 on its seat, but is not sufficiently strong to then raise the slide 105 valve 38 into the position shown in Fig. 1.

It will be apparent, however, that the spring 50 could be made sufficiently strong to raise the slide 38, instead of relying upon the force of the compression to do this.

110 The valve construction embodying this invention possesses many advantages over those heretofore used. The admission valve and exhaust valve are herein combined in an extremely simple and efficient structure calling for but few parts, only one spring for 115 example being required. It will be noted that the incoming mixture is drawn in over the valve disk 36, thus tending to cool the latter. This enables a much larger valve disk, and consequently valve opening, to be 120 used, as the danger of warping, due to the extreme heat, is thereby greatly reduced. The use of a large valve opening enables the explosive mixture to be quickly drawn into 125 the cylinder, but more particularly, and what is of still greater importance, a very rapid, free and complete exhaust of the waste gases, which means a great gain in efficiency, power and flexibility. It will also be noted that but a relatively slight move- 130

ment of the valve members is required to open and close the ports, and as this movement is effected by cams, it can be made to take place almost instantly, thus giving 5 the advantage and benefit of a full opening of the port at the outside. The whole structure of the valve members and ports makes for the most rapid and free exhaust.

As shown in Fig. 1, the use of this valve 10 not only does not interfere with the use of the substantially spherical combustion chamber which is considered the ideal one, but fits perfectly into a combustion chamber of that shape,

15 It will be apparent that the invention is applicable to multiple cylinder engines by simply multiplying the number of cams upon the shaft 64 to correspond to the number of cylinders, and angularly adjusting said 20 cams to cause each one to actuate its valve mechanism in suitable time relation.

It will be observed that in the structure embodying applicant's invention, but a single valve is subjected to the pressure incident to the periods of compression and firing, instead of a plurality, as in other constructions used. This greatly contributes to the prevention of leakage.

It will be understood that the terms 30 "upper," "lower," etc., as applied to the structure herein, are merely terms of distinction applied to the specific drawings hereto annexed to facilitate a more ready understanding of them and have no significance as applied to the generic principles of this invention, various embodiments of which may be made, wherein the relation of the parts thus referred to may be reversed or variously altered.

40 It will be understood that, while the invention is herein described as embodied in the details illustrated, the invention is not to be considered as circumscribed by or limited to these details, or any of them, but 45 that the said details may be variously modified within the true scope of the invention, which is definitely set forth in the claims.

Claims:

1. In an internal combustion engine, a 50 cylinder provided centrally of its head with a bore; an admission chamber having admission ports communicating with said bore; an exhaust chamber having exhaust ports communicating with said bore; a slide 55 valve mounted for sliding movement in said bore and provided with ports adapted to communicate with said admission ports and said exhaust ports, and in communication with an opening in said slide valve adapted 60 to communicate with the interior of the cylinder; a plug closing the outer end of said bore; a puppet valve adapted to close the opening from the slide valve into the interior of the cylinder and having its stem 65 mounted for relative individual inward

or downward longitudinal movement and joint upward or outward movement in said slide valve and plug; and actuating mechanism, including a spring and cam means, for actuating said slide valve and puppet 70 valve.

2. In an internal combustion engine, a cylinder provided with a bore; an admission chamber having admission ports communicating with said bore; an exhaust chamber having exhaust ports communicating with said bore; a slide valve mounted for sliding movement in said bore and provided with ports adapted to communicate with said admission ports and said exhaust 75 ports and in communication with an opening in said slide valve adapted to communicate with the interior of the cylinder; a puppet valve adapted to close the opening from said slide valve into the interior of 80 the cylinder and actuate the slide valve; and actuating mechanism for said slide valve and said puppet valve.

3. In an internal combustion engine, a cylinder having an admission port to admit the explosive mixture into the cylinder, and an exhaust port for the escape of the waste gases from said cylinder; a slide valve provided with a central opening 90 adapted to communicate with the interior of the cylinder, and with a port communicating with said central opening and adapted to communicate with said exhaust port and admission port; a valve member adapted to close said central opening in the slide valve and actuate the latter; and actuating mechanism for actuating said slide valve 95 and valve member.

4. In an internal combustion engine, a cylinder having an admission port for the admission of the explosive mixture to the interior of the cylinder and an exhaust port for the escape of the waste gases therefrom; a sleeve valve, the interior of which is adapted to communicate with the interior of the cylinder, and through a port in said slide valve with said exhaust port and admission port; a valve member actuating the slide valve and for controlling the communication of the interior of said slide valve 115 with the interior of the cylinder; and actuating means for said slide valve and valve member.

5. In an internal combustion engine, a cylinder, a two diameter valve bore in the head thereof, inlet and exhaust ports in said bore, a two diameter slide valve to provide an offset closure for the exhaust port, and having a puppet valve seat, a puppet valve 120 cooperating with and adapted to seat on the slide valve to control both the admission of the fuel and the exhaust of the waste gases from the cylinder, and means to operate said valves.

6. In an internal combustion engine, a 130

1 cylinder having an admission port and an exhaust port for admitting the explosive mixture to said cylinder and the exhaust of the waste gases therefrom, respectively; 5 a plurality of valves one of which seats upon the other for controlling said exhaust port and admission port co-operating jointly to control both said admission port and exhaust port; and operating means for one 10 of said valves and, through the agency thereof, for the other valve in one direction only.

7. In an internal combustion engine, a cylinder having an admission port and an 15 exhaust port for admitting the explosive mixture to said cylinder and the exhaust of the waste gases therefrom, respectively; two valves, the one located axially of and providing a seat for the other and operated thereby in one direction only, co-operating 20 jointly to control both said admission port and said exhaust port; and operating means for said valves.

8. In an internal combustion engine, a cylinder having an admission port and an 25 exhaust port for admitting the explosive mixture to said cylinder and the exhaust of the waste gases therefrom, respectively; two concentrically located valves, one 30 seated open the other and co-operating jointly to control both said admission port and said exhaust port; and operating means for said valves to actuate one through the agency of the other in one direction 35 only.

9. In an internal combustion engine, a cylinder provided with a bore having an admission port and an exhaust port for the admission of the explosive mixture to and the exhaust of the waste gases from 40 said cylinder, respectively; two concentrically located valves, one seated upon the other and operating in said bore and co-operating jointly to control both said admission port and said exhaust port; and 45 operating means for said valves to actuate one through the agency of the other in one direction only.

10. In an internal combustion engine, a cylinder, a two diameter valve bore in the 50 head, inlet and exhaust ports in said bore, a cooling chamber thereabout, a two diameter slide valve with an offset closure for the exhaust port, a puppet valve seated thereon, inlet and exhaust chambers within 55 said cooling chamber and having ports leading into the slide valve for communication with the cylinder.

11. In an internal combustion engine, a cylinder, a two diameter valve bore in the 60 head, inlet and exhaust ports in said bore, a two diameter slide valve with an offset closure for the exhaust port, a puppet valve seated thereon, inlet and exhaust chambers 65 having ports leading into the slide valve and communicating therethrough with the cylinder.

In testimony whereof, I have signed my name to this specification.

OSCAR C. JANSSEN.
